UNITED STATES PATENT OFFICE.

FRANKLIN E. ARNDT, OF GALION, OHIO, ASSIGNOR TO THE GALION IRON WORKS & MFG. CO., OF GALION, OHIO, A CORPORATION OF OHIO.

STONE DISTRIBUTOR AND LEVELER.

Application filed November 20, 1922. Serial No. 602,122.

To all whom it may concern:

Be it known that I, FRANKLIN E. ARNDT, a citizen of the United States, residing at Galion, in the county of Crawford and State 5 of Ohio, have invented certain new and useful Improvements in Stone Distributors and Levelers, of which the following is a specification.

This invention relates to road building 10 machines, and particularly to means for distributing and leveling road metal such as broken stone, gravel or other broken or comminuted material.

One of the objects of this invention is to 15 provide a stone spreader of this character of a very simple and effective construction and which is adapted to be attached to and drawn behind a truck and to receive the broken stone or other material from the 20 truck and discharge it onto the roadway in a layer, and in this connection to provide very simple means whereby the thickness of the layer of stone laid down may be controlled and the stone leveled.

25 A further object is to provide a construction of this character wherein a hopper is disposed at a height above the road bed, the bottom of the hopper being open and the hopper being fixed from any vertical adjustment; the thickness of the stone laid down upon the road bed being determined by means of a strike-off blade supported rearward but independently of the hopper and mounted so that it may be raised or lowered 30 to the desired height, thus doing away with the necessity of raising or lowering the hopper itself, which even when empty of stone is relatively heavy, and which when loaded is still more difficult to raise or lower, and 35 40 my construction permitting adjustment of the strike-off blade at any time without difficulty.

Other objects have to do with the details of construction and arrangement of parts 45 as will be hereinafter more fully stated.

My invention is illustrated in the accompanying drawings, wherein:

50 Figure 1 is a side elevation of a stone distributor constructed in accordance with my invention;

Figure 2 is a rear elevation of the same.

Referring to these drawings, 10 designates

a hopper-shaped container having downwardly converging, forward and rear walls 11 and the end walls 12, the body of the container being braced by the angle iron frames 13. The bottom of the hopper is open and the hopper is supported by means of runners 14 disposed inward of the ends of the hopper 10 and extending forward of the hopper and 55 being so disposed that the rear ends of the runners are approximately directly beneath the lower end of the forward wall of the hopper. These runners 14 are preferably formed of T-bars, though I do not wish to 60 be limited to this. Attached to the runners in any suitable manner are the upwardly and rearwardly extending supports 15, which at their lower ends are connected to transverse U-shaped bars 16, which at their ends are 65 attached to the runners 14. The upper ends of the brackets 15 are attached to angle irons 17, in turn attached to the upper and lower margins of the front wall of the hopper. The lower margin of the rear wall of the 70 hopper is provided with a longitudinally extending angle iron 18 having a horizontally projecting flange, and the upper margin of the rear wall of the hopper is also provided with the angle iron 19. The forward ends of the runners are provided with shackles 20, to which draft chains 21 are connected, these draft chains having rings at their ends whereby they may be attached to hooks 22, 75 in turn attached to the chassis of the truck A, the runners 14 being preferably disposed 80 inwardly of the wheels B.

Attached to the ends of the front wall of the hopper and preferably attached to the angle iron framing members 13 are the 85 brackets 23. These brackets have their lower edges on a level with the bottom of the hopper, and pivotally attached to these brackets and extending rearward laterally of the ends of the hopper are the arms 24. 90 These arms are pivoted at 24^a to the brackets 23 and extend rearward of the rear wall of the hopper and then downward and carry attached to their downwardly extending ends the strike-off blade 25. This strike-off 95 blade 25 has a length greater than the total length of the hopper so that it extends laterally beyond the draw bars or arms 24 and, therefore, beyond the ends of the hopper.

The strike-off blade is attached to the lower extremities of the downwardly bent ends of the draw bars or arms 24 by means of bolts 26 or in any other suitable manner. The 5 upper and lower edges of the blade 25 are preferably beveled and it will be obvious that when one edge of the blade becomes worn the blade may be shifted so as to bring the other edge downward. The lower edge 10 of the blade should be straight so as to strike off or level the upper face of the broken stone or other material deposited on the road bed from the hopper.

The rear ends of the arms of the draw bar 15 24 have attached thereto the rearwardly projecting handles 27 whereby these arms or draw bars may be lifted and adjusted, and for the purpose of holding the draw bars in any desired adjusted position, a plate 28 20 is riveted or otherwise attached or mounted upon the end walls of the hopper, which plate is provided with a plurality of perforations 29 or sockets. These sockets are arranged in an arc of a circle, the center of 25 which is the pivotal axis 24^a of the draw bars, and the draw bars or arms are held in their adjusted position by means of pins 30 inserted one through each draw bar into the corresponding socket. As illustrated, these 30 pins are held from accidental detachment by forming each pin with a hook-like portion 31 adapted to engage over the corresponding draw bar. When it is desired to withdraw the pin, of course the pin is to be turned in 35 its socket, lifting the hook-like portion 31 from the draw bar, then the pin may be pulled out, and when both pins are out it is obvious that the draw bars may be raised or lowered by means of the handle 27 so as to 40 adjust the strike-off blade to any desired height from the road bed.

In the practical use of this invention, it will be obvious that the truck body C discharges broken stone, gravel, slag, sand or 45 any other suitable material of a more or less comminuted or broken character into the hopper 10. This material is discharged through the open bottom of the hopper onto the roadway as the hopper is being dragged 50 along by the truck. As the hopper moves along discharging the load of material onto the ground, the strike-off blade 25 acts as a scraper, leveling off the material so as to give a layer of even thickness along the 55 whole width of the roadway or for a width depending upon the transverse length of the hopper. If a relatively thin layer of material is desired, the striking blade is lowered to its maximum extent, and if a thicker 60 layer is desired the strike-off blade is raised, thus varying the thickness of material deposited upon the road. The pivotal connection between the brackets 23 and the draw bars or arms 24 or between bolts 26 65 and arms 24 is loose enough to permit either

one of the draw bars to be raised or lowered relative to the other draw bar so as to thus cause the strike-off blade to be set at a slight inclination to the horizontal so that the layer of material deposited by the distributor is 70 slightly less in thickness at one end of the hopper than it is at the other. This is of particular value where it is desired that the crown of the road shall have a greater thickness of broken stone laid thereon than the 75 margin of the road, and obviously the hopper may have any desired length and capacity. The ability to easily raise or lower the strike-off blade is of particular advantage 80 where it is necessary to gradually increase the thickness of the material distributed from the hopper or decrease the thickness of this material as, for instance, where grades are being changed or slight hollows have to be 85 filled up.

The ground engaging members 14, which are preferably in the form of runners, are disposed inward of the ends of the hopper 10 so that one end of the hopper may overlap a layer of stone previously laid down. 90 If the runners were disposed at the ends of the hopper the runners would run along the edge of the layer of stone previously laid down and as a consequence there would be a valley between the two layers of stone 95 which would have to be afterwards filled up and struck off level. This is obviated by having the hopper extend laterally beyond the runners.

It is to be noted that one of the advantages of having the striking blade mounted upon the pivoted draw bars is that the striking blade is very readily shifted and is perfectly free when unlocked. If the striking blade were mounted upon one wall 100 of the hopper it would have to be mounted in guides and this would make it difficult to adjust the plate freely. The draw bars, however, constitute levers carrying the striking blade, these levers permitting the easy 105 raising or lowering of the striking blade. Inasmuch as the striking blade is not in contact with any part of the hopper, there is no chance for the striking blade to become rusted in place or for corrosion to act 110 upon the blade and hopper so as to cause adhesion between the two which would have to be broken in order to shift the striking blade.

I claim:—

1. A distributor for road material comprising a hopper having side and end walls and being open at the bottom thereof, road engaging supports for the hopper, and a striking off blade disposed rearward of the lower end of the hopper and normally extending below the level of the bottom of the hopper, members supporting said blade and pivoted for vertical adjustment, and means 125 engaging said members and adapted to hold 130

the blade in any vertically adjusted position.

2. A distributor for road material comprising a hopper having side and end walls and having an open bottom, road engaging supporting means for the hopper, a strike-off blade disposed rearward of the lower portion of the hopper, and arms pivotally supported upon the same and extending rearward of the hopper and to which the striking off blade is attached, said arms being vertically adjustable, and means for holding the arms in vertically adjusted positions.

15 3. A spreader for road material comprising a hopper having side and end walls and open at the bottom, road engaging supporting means for said hopper, arms pivotally connected to the hopper and extending rearward thereof, said arms being vertically adjustable, a striking off blade carried upon the rear ends of said arms and supported thereby and spaced from the rear wall of the hopper and means for holding the arms 25 in vertically adjusted positions.

4. A spreader for road material comprising a hopper having side and end walls and being open at the bottom thereof, means for supporting the hopper at a distance from the ground equal to the maximum depth proposed for the road material, a strike-off blade extending transversely of the line of draft and close to the hopper, and means for holding the blade fixed as against vertical 35 movement in either direction in relation to the hopper.

5. A distributor for road material comprising a hopper having side and end walls and open at the bottom, a road engaging support for the hopper, brackets mounted upon the hopper, draft bars pivotally mounted upon said brackets at each end of the hopper and extending rearward of the hopper and then downward, a striking off blade attached to the rear ends of the draft bars and movable therewith and normally spaced from the rear wall of the hopper, and means for holding said draft bars in vertically adjusted positions.

50 6. A distributor for road material comprising a hopper having side and end walls and open at the bottom, a road engaging support for the hopper, brackets mounted upon the hopper, draft bars pivotally mounted upon said brackets at each end of the hopper and extending rearward of the hopper and then downward, a striking off blade attached to the rear ends of the draft bars and movable therewith and normally spaced from the rear wall of the hopper, and means for holding said draft bars in vertically adjusted positions, the draft bars having rearwardly extending handles whereby they may be raised or lowered.

7. A distributor for road material comprising a hopper having side and end walls and an open bottom, ground engaging members disposed forward of the hopper and inward of the ends thereof, brackets supporting the hopper upon said ground engaging members, means attached to the ground engaging members whereby the hopper may be connected to a truck, draft bars pivotally connected operatively to the hopper and extending rearward at each end thereof to a point beyond the hopper, a striking off blade mounted upon said draft bars and vertically movable therewith, and means whereby the draft bars may be held in any vertically adjusted position.

8. A distributor for road material comprising a hopper open at the top and bottom and having side and end walls, runners disposed inward of the ends of the hopper and forward of the lower end of the front wall, means supporting the hopper upon the runners, a strike-off blade disposed rearward of and spaced from the rear wall of the hopper and normally extended below this rear wall, draw bars operatively pivoted upon the hopper and extending rearward at each end thereof and operatively connected to the striking off blade and having rearwardly extending handles, and means for holding the draw bars at different elevations with respect to the hopper to thereby adjust the height of the striking off plate from the ground.

9. A distributor for road material comprising a containing hopper having side and end walls and having a discharge opening in the bottom thereof, ground engaging means for supporting the hopper, a striking off blade disposed rearward of and spaced from the rear wall of the hopper, arms operatively pivoted upon the distributor at each end of the hopper and extending rearward thereof and to which the striking off blade is connected, means for holding said arms in vertically adjusted positions comprising a series of sockets carried by the end walls of the hopper and disposed concentrically to the pivotal axis of the arms, and a pin carried by each arm and insertible into any one of said sockets, said arms being separately adjustable to thereby control the angle of said plate.

10. A distributor for road material comprising a hopper having side and end walls and having an open bottom, road engaging supports for the hopper supporting the bottom of the hopper at a height from the ground equal to the maximum depth of material to be distributed upon a road, and vertically adjustable means disposed at the rear of the hopper and normally extending below the bottom of the hopper for striking off and leveling the material discharged through the bottom of the hopper.

11. A spreader for road material comprising a hopper having an open bottom, means for supporting the hopper elevated from a road, a strike-off blade disposed rearward of and spaced from the rear wall of the hopper and extending transversely of the line of draft and close to the hopper,

and vertically adjustable means for supporting said strike-off blade and holding the blade fixed as against vertical movement in either direction with relation to the hopper.

In testimony whereof I affix my signature.

FRANKLIN E. ARNDT.
